US00D973515S

(12) **United States Design Patent** (10) Patent No.: **US D973,515 S**
(45) Date of Patent: ** *Dec. 27, 2022

(54) **PRODUCT DISPLAY UNIT**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **Liane Fang**, Redwood City, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Peter Russell-Clarke**, San Francisco, CA (US); **Charles A. Schwalbach**, Menlo Park, CA (US); **Benjamin Andrew Shaffer**, San Jose, CA (US); **Mikael Silvanto**, San Francisco, CA (US); **Christopher J. Stringer**, Woodside, CA (US); **Clement Tissandier**, San Francisco, CA (US); **Eugene Antony Whang**, San Francisco, CA (US); **Sheng Yang**, Mountain View, CA (US); **Rico Zörkendörfer**, San Francisco, CA (US)

(73) Assignee: **Apple Inc.**, Cupertino, CA (US)

(*) Notice: This patent is subject to a terminal disclaimer.

(**) Term: **15 Years**

(21) Appl. No.: **29/704,807**

(22) Filed: **Sep. 6, 2019**

(57) **CLAIM**

The ornamental design for a product display unit, as shown and described.

DESCRIPTION

FIG. 1 is a bottom front perspective view of a product display unit showing the claimed design;
 FIG. 2 is a right side view thereof;
 FIG. 3 is a left side view thereof;
 FIG. 4 is a top view thereof;
 FIG. 5 is a bottom view thereof;
 FIG. 6 is a front view thereof;
 FIG. 7 is a rear view thereof; and,
 FIG. 8 is a front view of the product display unit in an environment in which it may be used.
 The dashed broken lines in the figures show portions of the product display unit and environment that form no part of the claimed design.
 The dot-dash broken lines in the figures show boundaries that form no part of the claimed design.

1 Claim, 6 Drawing Sheets**Related U.S. Application Data**

a continuation of application No. 29/539,248, filed on Sep. 11, 2015, now Pat. No. Des. 793,856.

(58) Field of Classification Search

USPC D9/671, 736, 749, 755, 759; D7/553.2, D7/624
